UNITED STATES PATENT OFFICE.

FREDERICK A. IVES, OF CHESHIRE, CONNECTICUT, ASSIGNOR TO THE CHESHIRE MANUFACTURING COMPANY, OF SAME PLACE.

DESIGN FOR A LOOP FOR GARMENT-CLASPS.

SPECIFICATION forming part of Design No. 25,091, dated January 28, 1896.

Application filed November 25, 1895. Serial No. 570,118. Term of patent 14 years.

To all whom it may concern:

Be it known that I, FREDERICK A. IVES, of West Cheshire, in the county of New Haven and State of Connecticut, have invented a new Design for Loops for Garment-Clasps; and I do hereby declare the following, when taken in connection with the accompanying drawings and the letters of reference marked thereon, to be a full, clear, and exact description of the same, and which said drawings constitute part of this specification, and represent, in—

Figure 1, a face view; and Fig. 2, an edge view.

This invention relates to a design for the loops of garment-clasps; and it consists in the configuration as hereinafter described, and shown in the accompanying illustrations.

As herein shown, the loop consists of a perforated plate A, bar B parallel with said plate, but in a different horizontal plane, and connected at its ends with the plate by arms C, all as shown in the accompanying illustrations.

I claim—

The design for loops for garment-clasps as shown in the accompanying illustrations.

In testimony whereof I have signed this specification in the presence of two subscribing witnesses.

FREDERICK A. IVES.

Witnesses:

ALEXANDER W. WELTON,
TITUS B. IVES.
